UNITED STATES PATENT OFFICE.

FRANK C. WARDALL, OF BOONE, IOWA.

FLAG, PENNANT, AND SIMILAR EMBLEM.

1,260,104.

Specification of Letters Patent. Patented Mar. 19, 1918.

Continuation in part only of application Serial No. 92,042, filed April 18, 1916. This application filed December 7, 1916. Serial No. 135,613.

To all whom it may concern:

Be it known that I, FRANK C. WARDALL, a citizen of the United States, and a resident of Boone, Iowa, have invented certain new and useful Improvements in Flags, Pennants, and Similar Emblems, of which the following is a specification, accompanied by drawings.

This application is a continuation in part 10 only of my application for flags, Serial No. 92,042, filed April 18, 1916.

This invention relates to metallic flags, pennants or emblems of similar character. The object of the invention is to produce 15 such a flag or pennant which will be more durable and lasting than one made of cotton, silk, bunting or cloth of any kind. Cloth flags are of short duration when placed upon a flag pole or other support and 20 exposed to all kinds of weather and winds. My metallic flag, which is designed to have the appearance of a cloth flag waving in the wind, will last for many years in spite of the wind, and even if the first cost should 25 be a little more than an ordinary flag, the cost per year would be small.

The preferred forms of the invention are illustrated in the accompanying drawings, in which—

30 Figure 1 is a side view of a metallic flag supported on a flag pole;

Fig. 2 is a side view of the other side of the flag from that illustrated in Fig. 1;

Fig. 3 is an enlarged detail view partly 35 broken away of a portion of the same side of the flag as that illustrated in Fig. 2;

Fig. 4 is a top plan view partly broken away of the flag;

Fig. 5 is a top plan view partly broken 40 away of a modification;

Fig. 6 is a diagrammatic side view of a pennant form of emblem; and

Fig. 7 is a side view of a modification of 45 the flag.

It is essential that the frame of the flag or pennant should be strong and stiff with some flexibility, and the frame should be 50 preferably braced as by means of struts, so that it will maintain its initial shape when standing out straight from the flag pole, for instance, and subjected to the wind. It is not necessary that the flag pole be upright, for the flag or pennant may be suspended or hung from a support at any angle desired.

55 Referring especially to Fig. 2, showing the

reverse side of a flag, the frame A, B, C may be composed of solid or hollow rods, channels, angles, or I-beam sections and this frame may be of iron or aluminum or other suitable material. The portion A of the 60 frame is suitably bent or curved, as indicated in the drawings, and the portions B and C are bent along sinuous or wavy lines, so that the flag or emblem has the appearance of waving in the wind when supported 65 on a flag pole or other support. If the frame is made in sections, the parts are brazed or otherwise secured together, and in the form of the invention shown in Figs. 1 and 2, the frame could be made of three sections A, B 70 and C. It will be observed that the general outline of the flag formed by the sections A, B and C, is triangular, in order to carry out the simulation of a rectangular flag waving in the wind.

The frame is braced by suitable transverse braces, which preferably comprise the main brace D extending in a general diagonal direction across the frame, and the crossed braces E, F and G, H which are secured to 75 the frame in the sections formed by the dividing main brace D. The main brace D and the brace E which form the main struts are preferably of heavier material than the auxiliary braces F, G and H, and, in fact, 80 the braces F, G and H could be made of strong wire which will give flexibility to the whole frame. The heavier main braces D and E are brazed or otherwise secured to the main frame and the lighter braces F, G and 85 H which may be formed of wire are secured to the frame and main braces, as by wrapping the ends of the wire around the same, this detail being shown in Fig. 3. I am not 90 to be understood as limiting the invention 95 to the particular form and arrangement of braces shown in the drawings, but I have found that the design of struts indicated produces excellent results and the flag or pennant is maintained substantially in its 100 original shape, even with hard buffeting by the winds.

The braces indicated are especially adapted to keep the frame from sagging, which is 105 an important element of the device.

Upon the frame so constructed is suitably stretched and secured wire mesh or net J. This wire mesh or net should be of sufficiently heavy material to withstand considerable strain and the mesh may be con- 110

veniently fastened to the frame by bending the edges *K* of the mesh over the frame and securing them to the mesh as by means of the rivets *L*, as indicated in detail in Fig. 3, 5 but other modes of fastening may be devised. Additional light wires *O* may be wrapped around the braces and interwoven with the wire mesh to aid in holding it in place, and to keep it taut on the frame. The 10 base or foundation of metal framing, struts and wire mesh, is thus formed in the outline of a flag, pennant or similar emblem, so constructed that it has a wavy appearance and outline. 15 The symbols, characters or ornamentation representing the design of the emblem are suitably provided or outlined upon the base or foundation constructed as described. In the form of the invention shown in Figs. 20 1 to 6, these symbols or characters are formed of sheet metal suitably cut or otherwise formed in the proper shapes to carry out the design of the emblem. These metal forms are then suitably secured to the foundation of frame and wire mesh in any suitable manner, as by means of the rivets *P* and if desired wire *O'* may be wrapped around the frame and passed through the metal symbols to hold them on to the frame 25 and struts or to the wire mesh, as indicated in Fig. 3.

In the case of the representation of the American flag, as shown in Figs. 1 and 2, a lozenge or diamond shaped piece of metal *R* 30 has star-shaped openings *S* cut therein in such manner as to carry out the representation of a field of stars seen in perspective, and this metal sheet *R* is fastened as described to the frame and wire mesh. The 35 field will be colored blue on this plate and the light shining through the star-shaped openings will give the appearance of white stars, although, if desired, the mesh could be painted white before the field of stars is placed thereon. The painting also preserves the metal strands of the mesh.

The stripes are formed of metal strips *T* and suitably shaped to represent wavy lines. These strips may be colored red and are secured to the frame work and mesh by the 40 means described, or other suitable fastening devices. If the metal strips are colored red, the white stripes are represented by the open mesh along the lines *U* and all the 45 portions of the mesh uncovered by metal are preferably left open, even if painted white or some other color, in order to permit the wind to blow through and thus reduce the wind resistance on the flag. When 50 finished, the flag or other emblem forms a series of curves and wavy lines, which makes the flag appear as if it were waving in the air.

Suitable and convenient means for fastening the flag to a pole or other support 55

are provided. In this instance the upper portion of the frame is preferably provided with an eyelet *a* to be fastened to the halyard *b*, and the lower portion of the frame is provided with a fork *c* adapted to embrace the flag pole *d*. As shown, the halyard *b* passes over the pulley *e*, and the halyard *f* is also secured to the eyelet *a* and may, if desired, be given a turn around the fork *c* at the point *g*. By this means the 70 flag may be raised and lowered on a vertical pole and the fork *c* maintains the flag in outstanding position and permits it to swing around the flag pole in the nature of a weather-vane. The flag will thus be blown 75 by the wind and owing to its construction, which itself gives the appearance of waviness, it is difficult to distinguish my flag made of metal from a flag made of cloth or other fabric. 80

An obvious modification of the invention would consist of forming the symbols out of sheet metal and coloring them as indicated in Fig. 6. These symbols, if stars, for example, could be fastened to the wire mesh 85 and the field could be painted blue on the wire mesh. In order, if desired, to have both sides of the flag appear exactly the same, the metal symbols in the form of a field of stars and stripes formed of metal 90 could be fastened on the opposite side of the flag, as illustrated in Fig. 5, which shows a frame having metal portions on both sides.

In Fig. 6 a diagrammatic view of a pennant form of emblem is shown, having the same general construction of frame, struts, wire mesh and ornamentation, as shown in Figs. 1 and 2.

In Fig. 7 a modification of the invention 100 is shown in which the frame and wire mesh forming the foundation is like that heretofore described, but instead of using symbols cut out of metal, the ornamentation provided upon the mesh is painted thereon. 105 The field *k* for the stars is painted blue and the stars may either be painted white on the mesh or the mesh could be left unpainted. The stripes *o* are painted red and the portions of mesh *p* between the stripes are 110 painted white or left unpainted. All or some of the painted portions may be left with the mesh open, or the field for the stars and the red stripes may be so painted that the openings in the mesh are closed to make 115 solid portions.

The flag or emblem is very light and is not in any way affected by weather conditions. It is never wrapped around the flag staff or frozen to the flag staff, as is cloth. 120 It is always unfurled and does not depend upon the breeze to float it. It will last practically indefinitely and due to its porous or open mesh construction permits the wind to pass through it, thereby reducing wind re- 125 130

sistance. It is "alive" in the sense that it appears to be moving or alive, as in the case of a cloth flag, and it can be left upon a flag pole day and night, if desired. It furthermore has substantially the same appearance 5 in cloudy as well as in fair weather.

I claim and desire to obtain by Letters Patent the following:

1. A metal flag, pennant or emblem of 10 similar character, comprising a metallic frame forming the outline of the emblem, said frame being bent along sinuous or wavy lines to simulate movement in the wind, transverse braces secured to said frame, wire 15 mesh fastened to the frame and braces, and symbols or characters representing the design of the emblem provided upon the wire mesh.

2. A metal flag, pennant or emblem of 20 similar character, comprising a metallic frame forming the outline of the emblem, transverse braces secured to said frame, wire mesh fastened to the frame and braces, and symbols or characters representing the 25 design of the emblem provided upon the wire mesh, in solid colors, the remaining portions of the mesh being left open to reduce wind pressure and representing the white portions of the emblem by the light passing 30 through them.

3. A metal flag, pennant or emblem of 35 similar character, comprising a metallic frame forming the outline of the emblem, said frame being bent along sinuous or wavy lines to simulate movement in the wind, transvers braces secured to said frame, wire mesh fastened to the frame and braces, and symbols or characters formed of sheet metal 40 representing the design of the emblem secured to the wire mesh.

4. A metal flag, pennant or emblem of similar character, comprising a metallic

frame forming the outline of the emblem, transverse braces secured to said frame, wire mesh fastened to the frame and braces, and 45 colored symbols or characters formed of sheet metal representing the design of the emblem secured to the wire mesh and to the said frame and braces, the uncovered portions of the mesh being left open to reduce 50 wind pressure and representing the white portions of the emblem by the light passing through them.

5. A metal flag, pennant or emblem of similar character, comprising a metal frame 55 forming the outline of the emblem, said frame being bent along sinuous or wavy lines to simulate movement in the wind, crossed braces forming struts for stiffening the frame and preventing it from losing its 60 initial shape, wire mesh secured to said frame and braces, and symbols or characters of sheet metal cut to the desired forms to represent the design of the emblem and suitably colored, secured to said wire mesh, 65 the portions of the mesh remaining uncovered by said sheet metal symbols remaining open to reduce wind pressure.

6. A metal flag, pennant or emblem of similar character, comprising a rigid frame, 70 the upper portion of the frame being provided with means for attachment to a support or halyard, and the lower portion of the frame being provided with a rearwardly projecting fork adapted to coöperate with a support and maintain the emblem in 75 proper outstanding pivotal relation thereto.

In testimony whereof I have signed this specification in the presence of two subscribing witnesses.

FRANK C. WARDALL.
